UNITED STATES PATENT OFFICE.

HERMAN A. FISHER, OF WORCESTER, MASSACHUSETTS.

ROLLING-MILL BEARING.

Application filed September 1, 1925. Serial No. 53,931.

This invention relates to a journal or roll bearing for use in machines in which the bearings sustain excessively heavy pressure and is more particularly an improvement on the 5 journal described and claimed in my copending application filed January 16, 1925, Serial Number 2941.

It is the general object of my invention to improve the construction of such bearings 10 and to provide improved means for lubricating and cooling the same. With this general object in view, one feature of the invention relates to the provision of a journal in which a liner forms a fraction of the bearing surface 15 of the journal and in which a chamber, preferably coextensive with and adjacent the liner is supplied with a medium for cooling the liner and in which lubricant is furnished through a port near that end of the liner 20 which is adjacent the path of approach of the roll neck, which lubricant will be picked up by said roll neck and be spread over the liner and prevent undue heating of the liner and lubricant.

25 A further feature of the invention is the provision of journal box or bearing having a liner, a cooling chamber coextensive with the liner and in communication with an arcuately shaped channel having one face open 30 to the roll neck disposed in the journal and embracing a greater portion of the roll neck so that a cooling medium supplied to the chamber and channel will come in direct contact with the roll neck and thereby maintain the liner and roll neck at a proper working 35 temperature, packing rings being provided to prevent the loss of fluid from the ends of the journal.

This invention will be best understood 40 from a consideration of the following detailed description, in view of the accompanying drawing forming a part of the specification; nevertheless it is to be understood that the invention is not confined to the disclosure, being susceptible of such changes and 45 modifications which shall define no material departure from the salient features of the invention as expressed in the appended claims.

50 Figure 1 is an end view of one form of the journal.

Figure 2 is a longitudinal vertical section taken along the line 2—2 of Figure 1.

55 Figure 3 is a transverse vertical section taken along the line 3—3 of Figure 2.

Figure 4 is a transverse vertical section taken along the line 4—4 of Figure 2.

Figure 5 is a rear end view of a modified form of the journal.

Figure 6 is a longitudinal vertical section 60 taken along the line 6—6 of Figure 5.

Referring more particularly to the drawings 10 designates a roller employed in rolling mills and provided with a roll neck 11 formed on the end of the roll and of reduced 65 diameter.

The roll neck is received within a longitudinal passage 12 in a casing which is composed of two sections 13 and 14. The upper section 13 is of less thickness than the lower 70 section 14 and is removably secured to the lower section by bolts 15. The upper section is convexed as shown at 16 and has cut-out portions 17 at the ends thereof in which are snugly fitted arcuately shaped carrier blocks 75 18, the blocks being so designed as to form a continuation of the convexed portion of the section 13 and provide bearing surfaces for the opposite ends of the roll neck 11.

That portion of the wall of the passage 80 which lies along the bottom of said passage and included in the lower section 14 of the casing is cut away longitudinally and circumferentially to provide a seat 19 for an arcuately shaped liner 20 which has its 85 curved active face 21 raised above the wall of the passage and in engagement with the surface of the roll neck 11 so that the roll neck will not come in contact with the walls of the passage and thus prevent sealing of 90 the passage. The liner 20 is made of some nonfriction metal well known in the art. A longitudinal edge 22 of the liner is beveled adjacent a port 43 to permit lubricant from 95 said port to be readily drawn in between the liner and the roll neck with the least possible friction.

The section 14 is cored below the liner 20 and close to said liner to provide arcuately shaped passages 23 and 24 forming 100 cooling chambers preferably coextensive with the liner 20. These passages are connected together intermediate their ends by transverse passages 25 so that proper circulation of a cooling medium is afforded. A 105 duct 26 connected with passage 23 forms an inlet for the cooling medium and terminates at 27 in the end wall of the section 14. A duct 28 connects the passages with a channel or recess 29 to be described. 110

The walls of the passage 12 are cut away for a portion of the length of the sections 13 and 14 as shown in Figures 2 and 6, along the full arcuately shaped inner face of the section 13 and along portions adjacent the opposite edges of the liner 20 to provide said channel 29. It will be noted that the channel embraces the greater portion of the circumferential area of the roll neck 11 and since the face of the channel is entirely open, the roll neck will be exposed over the greater portion of its surface to a cooling medium supplied from the cooling chambers 23 and 24. A discharge duct 30 running the length of the section 14 has an elongated port 31 connecting said duct with the channel 29 at a point on the side of the liner 20 which is opposite the inlet duct 28. The duct 31 terminates at 32 in the rear end 20 of the section 14.

A cup-shaped member 33 is employed in the form shown in Figures 5 and 6 and has a flanged inner open end 34 bolted to the rear ends of the sections 13 and 14 and 25 housing a reduced end 35 of the roll neck 11. It must be borne in mind that the casings in the two constructions shown in Figures 1 to 4 inclusive and Figures 5 and 6 are identical. In addition, the casing in Figures 5 and 6 is provided with the cup-shaped member 33 to receive and distribute the cooling medium to the passages in the casing while in Figures 1 to 4 inclusive the cooling medium is supplied directly to the port 27 and duct 26 in the lower section 14. The closed end 37 of the cup-shaped member is provided with a central internally threaded opening 38 into which is adapted to be screwed a pipe connection through 40 which is supplied a cooling medium under pressure such as oil or water. The cup-shaped member has a hollow enlargement 39 depending therefrom providing a passage for the cooling medium from the member 33 to the duct 26, the passage registering with the port 27 in the end wall of the section 14. The cup is provided with perforated ears 40 whereby said cup is bolted to the sections 13 and 14. 50 The section 14 (Fig. 2) has a longitudinal duct 41 terminating in the rear end wall in a port 42 to which is adapted to be connected a pipe for supplying lubricant under pressure. An elongated narrow port 43 connects the duct 41 with the central passage 12 in the casing and at that beveled or chamfered longitudinal edge of the liner 20 which is adjacent the path of approach of the roll neck 11 so that the lubricant from the duct will be picked up by the revolving roll neck and spread over the active surface 21 of the liner. The lubricant is carried on the surface of the roll neck in a thin film and in direct contact with the cooling medium in the channel 29 where it forms with

the cooling medium an emulsion of water and oil.

In order to prevent the loss of lubricant and cooling medium from the opposite ends of the casing, a packing ring 44 is set in a V-shaped groove at the rear end of the casing and held in place by the flanged end 34 of the cup 33 in Figures 5 and 6, while in Figs. 1 to 4 a ring 34* which has a similar design to the flange 34 on the cup-shaped member 33 is bolted to the sections 13 and 14 to hold the packing ring in place. Packing rings 45 and 46 are disposed at the inner end of the casing and between said end and a shoulder 47 on the roller 10. A resilient wire ring 48 embraces ring 46 and aids in sealing the rings to the inner end of the casing.

When the rollers 10 are water cooled, a pipe may be inserted through a longitudinal passage in the roll neck for the purpose.

Having described the construction and advantages of my improved bearing, I do not wish to be limited to the details herein disclosed, otherwise than as set forth in the claims.

What I claim is:

1. A journal bearing for the roll neck of a roller having in combination a casing provided with a longitudinal passage to receive the roll neck, a liner, a portion of the passage being cut away to form a seat for said liner, said casing adjacent the liner being cored to provide a cooling chamber, the section of the casing which supports the liner being provided with a longitudinal duct opening into said passage adjacent one end of the liner for supplying lubricant to the surface of the roll neck, said roll neck being adapted when revolved to spread the lubricant over a face of the liner.

2. A journal bearing for the roll neck of a roller having in combination a casing provided with a longitudinal passage, a liner therein forming a portion of the wall of the passage and having one face above the said wall, the casing being provided with a cooling chamber adjacent the liner and coextensive with said liner, the wall of the passage being cut away for a greater portion of the circumference thereof to form a channel for a cooling medium so that a greater portion of surface of the roll neck is exposed directly to the cooling medium, the ends of said channel terminating adjacent the ends of the liner, the casing having a duct connecting the channel with the cooling chamber.

3. A journal bearing for a rotating member comprising a casing having a longitudinal opening arranged to receive said member, said casing being cored to form a cooling chamber adjacent said bearing opening but separated therefrom, and said chamber

permitting the passage of a cooling fluid therethrough, means for feeding lubricant to the rotating member at a fixed point in said casing, and means acting normally and continuously for conducting the cooling fluid from said cooling chamber to directly engage and cool the previously lubricated portion of the rotating member at a fixed point in said casing substantially spaced peripherally from the point of lubrication. 5

4. A journal bearing for a rotating member comprising a casing having a longitudinal opening arranged to receive said member, said casing being cored to form a cooling chamber adjacent said bearing opening but separated therefrom, and said chamber permitting the passage of a cooling fluid therethrough, and means axially disposed adjacent one edge of said cored portion for feeding lubricant to the rotating member, said cooling chamber along the opposite edge of the cored portion being in direct communication with the rotating member, whereby the cooling fluid from the cooling chamber may mix with the lubricant and further cool said rotating member. 10 15 20 25

5. A journal bearing for a rotating shaft comprising a casing having a segmental shaft-supporting portion and a recessed cooling portion with an open side adjacent

said shaft, said casing also having a cooling chamber closely adjacent said shaft-supporting portion but separated from said shaft, means to feed a lubricant directly to said shaft-supporting portion, and additional means acting normally and continuously to feed a cooling liquid through said cooling chamber and from said chamber to said recessed cooling portion in direct contact with said shaft and lubricant, whereby 35 40 45 said shaft is both lubricated and cooled.

6. A journal bearing for a rotating member comprising a casing having a segmental bearing portion, means to supply a lubricant to said rotating member adjacent the point where said member enters engagement with said bearing portion, said casing having a cooling chamber closely adjacent said bearing portion but separated from said rotating member, and additional means to 50 55 feed a cooling liquid through said cooling chamber and from said chamber in direct contact with the remaining portion of the periphery of said rotating member, said cooling liquid engaging said rotating member adjacent the point where the rotating surface of said member leaves said segmental bearing portion.
